UNITED STATES PATENT OFFICE.

HOWARD S. RODGERS, OF COVINGTON, KENTUCKY.

SIGNALING DEVICE FOR RAILWAY-CARS.

SPECIFICATION forming part of Letters Patent No. 635,891, dated October 24, 1899.

Application filed August 3, 1899. Serial No. 725,971. (No model.)

To all whom it may concern:

Be it known that I, HOWARD S. RODGERS, a citizen of the United States, and a resident of Covington, in the county of Kenton and State 5 of Kentucky, have invented certain new and useful Improvements in Signaling Devices for Railways and the Like, of which the following is a full, clear and exact description, reference being had to the accompanying drawings, forming part of this specification.

My invention relates to improvements in signaling devices, and is especially adapted for use on street-railways, in the operation of which the signal for starting and stopping is 15 ordinarily given the man in charge of the propelling mechanism by pulling a cord or strap attached to a gong or suitable mechanism within hearing range of the operator.

It is customary in the operation of street-20 railways to stop only on signal from the conductor and then only at a street intersection or some designated point, and no stops are made between any of these designated points or street intersections, and in case of an emergency there is no alarm or signal which may 25 be communicated to the operator in charge of the propelling mechanism to indicate the necessity of an immediate stop. Accidents frequently occur in various ways—as, for instance, the conductor may have given the starting-signal before the passenger has alighted from the car, or the clothing of the passenger alighting may have caught in some manner, or a passenger has endeavored to alight from 30 35 or board a moving car. Should the conductor at such times give the ordinary signal to stop, the car would probably be run to the next designated stopping-point and cover a considerable distance before stopping, and it

40 would often be the case that were it possible to communicate immediately some simple and unmistakable signal to the man in charge of the propelling-power serious injury to the passenger could be averted. It is true that 45 on some tramways three strokes of the gong are used as an emergency signal; but often in the excitement incident to such occasions this signal is not recalled by the conductor. Furthermore, this sort of signal is often unknown to the passengers, who may be aware 50 of the accident before the conductor, and therefore time would be lost in notifying him.

The object of my invention is to provide some simple and unmistakable signal for an immediate stop and one that can be operated 55 by the same cord or strap used for the ordinary starting and stopping signal.

In the drawings, Figure 1 is a side view of a signal-bell with my improvement. Fig. 2 is a bottom view of same with the cap of the 60 bell removed.

Like letters of reference indicate identical parts in both figures.

I have illustrated in the drawings a well-known construction of gong comprising body 65 portion *a* and cap *b*.

A is the "knocker," of the usual bell-crank construction, pivoted at *c*.

B is the bell-cord or strap, comprising ends *d e*, the end *d* controlling the bell-crank operating the usual knocker *A*. I have shown the end *d* provided with a coiled spring *f* and this end made more taut than end *e*, so that an ordinary pull on cord *B* will operate the knocker *A* without putting sufficient pull 75 on end *e* to operate the mechanism it is connected with.

As one form of mechanism for producing an emergency-signal I have shown the well-known ratchet-lever *h*, which meshes with a 80 small ratchet *i*, which in turn meshes with a small ratchet to which the small knockers *j j* are secured, whereby they are rotated, and as these knockers are loosely held the centrifugal force sends them out against the bell- 85 cap, producing a constant ring, the lever *h* being drawn back to its normal position by a small coiled spring *k*, so that the gong will sound during the forward and backward swing of the lever *h*. Connected with the lever *h* 90 is the other end of the bell-cord *e*.

It is obvious from the drawings and the above description that an ordinary pull on the bell-cord *B* will not produce the emergency-signal, but merely operate the usual knocker 95 to give the ordinary signals for starting and stopping the car; but if the bell-cord *B* is given a strong pull the spring *f* will of course expand and the end *e* also put under sufficient tension to pull the lever *h*, thus not only pulling the knocker *A*, but also operating the emergency-signal, which is caused by the revolving knockers *j j*. Thus it will be seen 100 that a simple yet effective signal is given by

the casual passenger, who from excitement would naturally, or by the conductor, who intentionally would, give a strong pull on the cord B.

5 I have described the end *d* as being supplied with a coiled spring *f*. It is of course obvious that instead of such a spring rubber or any elastic material might be used. So, also, in place of the mechanism shown and described 10 to produce the emergency-signal other mechanism may be used.

My invention of course may be applied to the bell or signal cord of steam-railways, elevators, and the like, and in the case of rail- 15 ways, for instance, instead of the mechanism above described a steam or air whistle or other signal may be used, or the end *e* of the cord may have connection with the mechanism for applying the air or electric brakes, as well as 20 giving some sort of signal.

While it is true that I have not shown the usual shape of gong in the drawings, it is of course obvious that such gong may be used and the end connecting with the usual knocker 25 or striker provided with a spring or elastic material and the mechanism for producing the emergency-signal added and the same connected to the bell-cord, thus making it possible to very readily equip a tramway. It is 30 obvious that any number of ends to the bell-cord may be employed, each end arranged to be operated when a certain amount of tension is applied to the main cord or strap, and thereby two, three, or any number of signals and 35 mechanism operated, and I do not limit myself to the mechanism as here shown and described; but

What I claim, and desire to secure by Letters Patent, is—

40 1. In a signaling device, a bell-cord bifurcated at its one end, one of said bifurcations having controlling connection with mechanism for producing an emergency-signal, the other bifurcation connecting with the usual 45 signaling device, and arranged to operate un-

der a normal tension, and means intermediate the main cord and usual signaling device to permit of such increase of tension whereby the emergency-signal bifurcation is made taut and said signaling device operated, substantially as and in the manner described. 50

2. In a signaling device, a bifurcated bell-cord, said bifurcations connecting with the usual signaling device and with mechanism for producing an emergency-signal, said bifurcations placed under varying tensions, and means intermediate the usual signal device and its connecting bifurcation, to permit of an increase of tension whereby the emergency-signal-controlling bifurcation is made taut 60 and the same operated, substantially as shown and in the manner and for the purpose described.

3. In a signaling device for tramways and the like, a bifurcated signal-cord, one of said 65 bifurcations connecting with mechanism for use in an emergency, and the other connecting with the usual alarm-signal, and means intermediate the usual signal and main signal-cord to permit of increased tension, where- 70 by the emergency-mechanism-controlling bifurcation is made taut and said mechanism actuated, substantially in the manner and for the purpose described.

4. In a signaling device for tramways and the like, a ramified signal-cord whose ramifications connect with the usual alarm-signal and other mechanisms for use in an emergency, and means intermediate the usual signal and its controlling ramification whereby 75 tension on the main signal-cord may be varied and the various ramifications made taut, thereby actuating the emergency mechanism, substantially in the manner and for the purpose described. 80
